UNITED STATES PATENT OFFICE.

WILLIAM H. STRICKLER, OF MOUNT PLEASANT, PENNSYLVANIA.

OVEN AND FURNACE DOOR.

SPECIFICATION forming part of Letters Patent No. 253,235, dated February 7, 1882.

Application filed June 23, 1881. (No model.)

To all whom it may concern:

Be it known that I, WM. H. STRICKLER, of Mount Pleasant, in the county of Westmoreland and State of Pennsylvania, have invented 5 certain new and useful Improvements in Oven and Furnace Doors; and I do hereby declare that the following is a full, clear, and exact description of the invention, which will enable others skilled in the art to which it appertains 10 to make and use the same, reference being had to the accompanying drawings, which form a part of this specification.

Figure 1 is a front view of my improved furnace-door. Fig. 2 is a horizontal sectional 15 view, and Fig. 3 is a detail view, in perspective, of one of the sections of the same.

Corresponding parts in the several figures are denoted by like letters of reference.

This invention relates to doors for coke- 20 smelting and other furnaces; and it consists in certain improvements in the construction of the same, which will be hereinafter fully described, and particularly pointed out in the claim.

25 In the drawings hereto annexed, A represents the front wall of the furnace, and B the door-opening of the same. C is the door-frame, and D D the doors, which are supported upon curved hinges, which enable them to close 30 tightly against the sides of the door-frame.

The doors consist of cast-metal front plates E, and backs F made of fire-brick, which are secured to the metallic front plates by means of bolts G, the heads of which, H, are sunk in 35 suitable recesses in the faces of the fire-brick and covered with fire-brick mud, which is after-

ward hardened by the heat to which it is exposed.

It will be seen that by this arrangement an empty space or air-space, I, is formed between 40 the front and back of the door. Access to this space is had through several openings, J, in the front door casting, the air thus admitted escaping at the top into the furnace.

From the foregoing description, taken in 45 connection with the drawings hereto annexed, the operation and advantages of my invention will be readily understood. The fire-brick which forms the inside of the doors is secured thereto by bolts, which are embedded therein, 50 and thus protected from excessive heat. The air-space, through which a current of cold air constantly passes, preserves the door from excessive heat or from burning out, and the device is as convenient and as easily manipulated 55 as furnace-doors now in use.

Having thus described my invention, I claim and desire to secure by Letters Patent of the United States—

In a furnace-door, the combination, with a 60 metallic front, of a fire-brick back bolted thereto, the said front and back being some distance apart, and the heads of the bolts embedded in the fire-brick, as described, for the purpose set forth.

In testimony that I claim the foregoing as my own I have hereto affixed my signature in presence of two witnesses.

WILLIAM HENRY STRICKLER.
